UNITED STATES PATENT OFFICE.

BERNARD STANLEY NELSON, OF NEW ORLEANS, LOUISIANA, ASSIGNOR TO A. M. LOCKETT & COMPANY, LTD., OF NEW ORLEANS, LOUISIANA, A CORPORATION OF LOUISIANA.

SPRAY NOZZLE.

Application filed September 10, 1927. Serial No. 218,621.

This invention relates to nozzles and more especially to the type designated as spray or diffusing nozzles which may be employed for a great many purposes, as for example, in conjunction with cooling towers, fire extinguishers, irrigation projects, fuel spray nozzles of Diesel oil engines, sewage treatment, spray pond installations, condensers, and other analogous uses, where an atmosphere, area or zone containing a uniform and maximum distribution of drops of liquid is required, and the sizes and density of the diffusion or distribution of said drops capable of being controlled by the character and arrangement of diffusing elements, and velocity and manner with which the liquid impinges or reacts against diffusing elements within the nozzle and after ejected and free of the nozzle.

20 The objects of the invention are:

First, to construct a diffusing or spray nozzle of the character herein indicated which will comprise few parts coacting continuously and with a high efficiency, low cost 25 of manufacture, easily installed and inspected, and repaired, if necessary, at a minimum of expenditure.

Second, to construct a spray nozzle in which the direction of flow of the liquid issuing or emerging from the nozzle will be such as to preserve the greater part of its original energy or velocity and thus be divided into a plurality of streams or portions which will be made to impact or impinge 30 against each other exterior of the nozzle and effect a maximum and proper diffusion or spraying of the liquid at a high efficiency with a lower initial pressure as compared with that now used in prior and similar 35 devices.

Third, to construct a spray nozzle in which the spraying or diffusion of the liquid is due to the action, cooperation or impact of a plurality of streams of the liquid after 40 emerging or issuing from and exterior of the nozzle, and wherein the spraying depends upon the action of the liquid exterior of the nozzle, and, hence, many conditions can be satisfied by varying the proportions 45 and shapes of the spreading elements to effect various degrees of intensity of spraying and extent of finally sprayed areas or zones.

Fourth, other objects and advantages of

the invention which will be manifest from 55 the detailed description of the construction and arrangement of the elements and cooperation of the same to be hereinafter disclosed.

The invention consists of structural characteristics and relative arrangement of elements which will be hereinafter more fully described and particularly pointed out in the appended claims.

In the drawings in which similar reference characters indicate the same parts in the several figures,

Figure 1 is a side elevation of one form of the spraying nozzle;

Figure 2 is a longitudinal section taken 70 on lines II—II of Figure 1;

Figure 3 is a transverse section taken on line III—III of Figure 1;

Figure 4 is a longitudinal section partly in elevation of a modified form of the invention;

Figure 5 is a section taken on line V—V of Figure 4;

Figure 6 is a side elevation of a further modified form of the invention;

Figure 7 is a section on line VII—VII of Figure 6;

Figure 8 is a side elevation of a further modified form of the invention; and

Figure 9 is a section on line IX—IX of 85 Figure 8.

Referring to Figures 1, 2 and 3, 10 is the barrel of the nozzle which is provided with a bore or axial passageway or opening 11 having at one of its ends an outlet 12 for the 90 liquid while at its other or inlet end 13 is formed a threaded section 14 for attaching said barrel and nozzle in communication with any suitable supply of liquid under pressure.

15 and 16 are a plurality of separated and superimposed diffusing or spraying elements which are rigidly and properly secured to each other and in proximity to the outlet 12 of the barrel 10 by means of oppositely disposed supports or uprights 17, which are preferably cast or made integral with the outer sections or surfaces of the superimposed diffusing or spraying elements 15 and 16 and the top section of the barrel 10, as 105 illustrated.

The diffusing or spraying element 16 adjacent to the outlet 12 is provided with an

opening 18, which registers with the axis of the central bore or axial opening 11 for purposes to be presently explained.

The undersides or surfaces 19 and 20, respectively, of the superimposed diffusing or spraying elements 15 and 16 are so formed, machined or molded as to provide such a shape or configuration that when the liquid under pressure passes through the axial 10 opening 11 and outlet 12, a part of said liquid will impinge against the said underside and properly shaped under surface 20 and be deflected into a separate and distinct stream of liquid S' , shown in dotted line in 15 Figure 2, and is annular in cross section in planes normal to the axis of the opening 11, while the other part of the liquid emerging from the outlet 12 will pass directly through the opening 18 of the element 16 and impinge against the properly dished under surface 19 of the diffusing or spraying element 15 and be deflected into a separate and distinct stream of liquid S^2 , as shown in dotted lines, and of umbrella-shape with its outer 25 section or end also of annular cross section in planes normal to the axis of the opening 11, as will be readily understood by reference to Figure 1.

Said two streams S' and S^2 after reacting 30 and impinging respectively against the surfaces 20 and 19 will issue from the nozzle and be bent downwardly and made to diverge towards each other and form a circular zone of impact at I, surrounding and 35 in proximity and properly removed from the diffusing or spraying members 15 and 16, and such impact of the streams S' and S^2 breaks up said streams into drops or an area or region of sprayed or diffused liquid A 40 beyond and encircling the zone of impact I, as clearly shown in Figure 2 and needs no further disclosure.

Figures 4 and 5 show substantially the same construction shown in Figures 1 and 2, 45 except the barrel 101 having axial opening 111 is provided with supports 171 carrying differently shaped separated and superimposed diffusing elements 151 and 161, said element 161 having opening 181. This 50 modification changes the shapes and direction of the resultant separated and independent streams of liquid S^3 and S^4 , as indicated in dotted lines, so that the zone of impact I' and region or area of sprayed liquid A' is 55 elevated and above the spraying elements 151 and 161, as plainly shown by the dotted lines in Figure 4 and self explanatory.

In Figures 6 and 7 a further modification 60 is depicted on substantially the same lines as illustrated in Figures 1 and 2, in which the barrel 102 having axial opening 112 is provided with supports 172 carrying separated and superimposed deflecting elements 152 and 162, said element 162 having opening 65 182. This modification differs from that

shown in Figures 1 and 2 in that the coating deflecting surfaces on the under sides of the spreading elements 152 and 162 and facing the axial opening 112 are provided with parallel flutes 191 and 201 arranged as 70 shown. This construction of operating elements 152 and 162 and their arrangement of parallel flutes 191 and 201 operates in the same manner as described with reference to Figures 1 and 2 but forms four distinct 75 streams of liquid S^5 , S^6 , S^7 and S^8 , and so changes the shapes and directions of the four resultant separated and independent streams of liquid S^5 , S^6 , S^7 and S^8 , so that a plurality or series of three zones of impact I^3 , I^4 and I^5 , and three regions or areas A^2 , A^3 and A^4 of sprayed liquid are created in the relation to each other and the spreading elements 152 and 162, as shown by the dotted lines in Figure 7. 80

Figures 8 and 9 show substantially the same construction as shown in Figures 6 and 7, except the barrel 103, having axial opening 113, is provided with supports 173, carrying separated and superimposed spreading elements 153 and 163, said element 163 having opening 183. This modification differs from that shown in Figures 6 and 7 in that coating deflecting surfaces on the under-sides of the spreading elements 153 and 163 90 and facing the axial opening 113 instead of being provided with parallel flutes 191 and 201, shown in Figures 6 and 7, are provided with staggered flutes 192 and 202 arranged as shown. This construction of spreading elements 153 and 163 with staggered flutes 192 and 203 operates in the same manner as described with reference to Figures 1 and 2, except that it also develops, similar to the modification shown in Figures 6 and 7, a 100 series of four distinct and independent streams of liquid S^9 , S^{10} , S^{11} and S^{12} , and so changes the shapes and directions of said four resultant streams S^9 , S^{10} , S^{11} and S^{12} , so that a plurality or series of three zones of impact I^6 , I^7 and I^8 , and three regions or areas of sprayed liquid are produced in the 110 relative position to each other and the spreading elements 153 and 163, as fully illustrated by the dotted lines in Figure 9. 115

Either of the two modifications shown and described with reference to Figures 6, 7, 8 and 9 is installed in such cases where a more dense diffusion or spray of the liquid is desired than is formed by the constructions 120 and arrangements disclosed with reference to Figures 1, 2, 3 and 4.

From the foregoing disclosure of the construction and arrangement of the cooperating elements of the improved spraying 125 nozzle and mode of operation of the same, it will be seen that all the objects and advantages recited in the statement of invention are capable of being efficiently carried out, and that the present invention by simple 130

changes in the angles of the emitted and impinging streams or sheets of liquid is enabled to satisfy a wide variety of forms of spray, and, hence, meet various and particular conditions for which the same may be called upon to meet.

- Furthermore, the construction of the herein disclosed form of nozzle permits comparative low pressures to be used which makes it
- 10 possible for a given capacity to use much larger openings in the present and improved nozzle than heretofore, and, hence, less liable to clogging or stoppage of the liquid flow than with a nozzle with smaller openings,
- 15 and, if desired, the pressure can be increased with larger openings without any material frictional losses, thereby enabling a large quantity of liquid to be handled with very few nozzles.
- 20 Also with a nozzle with large openings and use of low velocity of the liquid, it is possible to make an efficient nozzle without any machine work for the reason the friction at low velocity is not a serious matter, whereas
- 25 with high velocity type of nozzles, it is most essential that all friction surfaces of the moving liquid be highly polished or machined.

It will also be readily understood that

30 while I have shown and described the use of the minimum number or two as comprising the cooperating separated and superimposed diffusing elements, this number can be increased for special purposes in satisfying

35 problems of engineering involving spraying operation without departing from the present invention, as expressed in the claims.

What I claim is:—

1. A spray nozzle comprising a barrel member having an axial opening through which a stream of liquid may be discharged, of a spreading member attached to said barrel member in proximity to the discharge end and in alignment with said axial opening, said spreading member consisting of a plurality of separated and superimposed diffusing elements provided with coacting deflecting surfaces constructed and arranged on their sides facing the axial opening and adapted to be impinged upon by the liquid passing through said axial opening so that the liquid passing through the axial opening is divided into a plurality of separate and independent streams of liquid diverging towards and impinging against each other to form a zone of impact of said streams of liquid removed and in proximity to said spreading member and an area of sprayed or diffused liquid beyond said zone of impact.
- 45
2. A spray nozzle comprising a barrel member having an axial opening through which a stream of liquid may be discharged, of a spreading member attached to said barrel member in proximity to the discharge end and in alignment with said axial opening, said spreading member consisting of a plurality of separated and superimposed diffusing elements provided with coacting deflecting surfaces constructed and arranged on their sides facing the axial opening and adapted to be impinged upon by the liquid passing through said axial opening so that the liquid passing through the axial opening is divided into a plurality of separated and independent streams of liquid diverging towards and impinging against each other to form a plurality of separate and distinct zones of impact removed and in proximity to said spreading

end and in alignment with said axial opening, said spreading member consisting of a plurality of separated and superimposed diffusing elements provided with coacting deflecting surfaces constructed and arranged on their sides facing the axial opening and adapted to be impinged upon by the liquid passing through said axial opening so that the liquid passing through the axial opening is divided into a plurality of separate and independent streams of liquid annular in cross-section in planes normal to the axis of the opening and diverging towards and impinging against each other to form a zone of impact of said streams of liquid removed and in proximity to said spreading member and an area of sprayed or diffused liquid beyond said zone of impact.

3. A spray nozzle comprising a barrel member having an axial opening through which a stream of liquid may be discharged, of a spreading member attached to said barrel member in proximity to the discharge end and in alignment with said axial opening, said spreading member consisting of a plurality of separated and superimposed diffusing elements, one of said elements next to the axial opening provided with an aperture, said diffusing elements provided with coacting deflecting surfaces constructed and arranged on their sides facing the axial opening and adapted to be impinged upon by the liquid passing through said axial opening so that the liquid passing through the axial opening and opening in said diffusing element next to said axial opening is divided into a plurality of separate and independent streams of liquid diverging towards and impinging against each other to form a circular zone of impact between said streams of liquid removed and in proximity to said spreading member and an area of sprayed or diffused liquid beyond said zone of impact.

4. A spray nozzle comprising a barrel member having an axial opening through which a stream of liquid may be discharged, of a spreading member attached to said barrel member in proximity to the discharge end and in alignment with said axial opening, said spreading member consisting of a plurality of separated and superimposed diffusing elements provided with coacting fluted deflecting surfaces constructed and arranged on their sides facing the axial opening and adapted to be impinged upon by the liquid passing through said axial opening so that the liquid passing through the axial opening is divided into a plurality of separated and independent streams of liquid diverging towards and impinging against each other to form a plurality of separate and distinct zones of impact removed and in proximity to said spreading

member and a plurality of separated areas of sprayed or diffused liquid beyond said zones of impact.

5. A spray nozzle comprising a barrel member having an axial opening through which a stream of liquid may be discharged, of a spreading member attached to said barrel member in proximity to the discharge end and in alinement with said axial opening, said spreading member consisting of a plurality of separated and superimposed diffusing elements provided with coacting staggered fluted deflecting surfaces constructed and arranged on their sides facing the axial opening and adapted to be impinged upon by the liquid passing through said axial opening so that the liquid passing through the axial opening is divided into a plurality of separate and independent streams of liquid diverging towards and impinging against each other to form a plurality of separate and distinct zones of impact removed and in proximity to said spreading member and a plurality of separated areas of sprayed or diffused liquid beyond said zones of impact.
6. A spray nozzle comprising a barrel member having an axial opening through which a stream of liquid may be discharged, of a spreading member attached to said barrel member in proximity to the discharge end and in alinement with said axial opening, said spreading member consisting of a plurality of separated and superimposed diffusing elements, one of said elements next to the axial opening being provided with an aperture, said diffusing elements provided with coacting fluted deflecting surfaces constructed and arranged on their sides facing the axial opening and adapted to be impinged upon by the liquid passing through said axial opening and opening in said diffusing element next to said axial opening so that the liquid passing through the axial opening is divided into a plurality of separate and independent streams of liquid diverging towards and impinging against each other to form a plurality of separate and distinct zones of impact removed and in proximity to said spreading member and a plurality of separated areas of sprayed or diffused liquid beyond said zones of impact.

7. A spray nozzle comprising a barrel member having an axial opening through which a stream of liquid may be discharged, of a spreading member attached to said barrel member in proximity to the discharge end and in alinement with said axial opening, said spreading member consisting of a plurality of separated and superimposed diffusing elements, one of said elements next to the axial opening being provided with an aperture, said diffusing elements provided with coacting staggered fluted deflecting surfaces constructed and arranged on their sides facing the axial opening and adapted to be impinged upon by the liquid passing through said axial opening and opening in said diffusing element next to said axial opening so that the liquid passing through the axial opening is divided into a plurality of separate and independent streams of liquid diverging towards and impinging against each other to form a plurality of separate and distinct zones of impact removed and in proximity to said spreading member and a plurality of separated areas of sprayed or diffused liquid beyond said zones of impact.

8. A spray nozzle comprising a barrel member having an opening through which a stream of liquid may be discharged, of a spreading member attached to said barrel member in proximity to the discharge end of said opening, said spreading member consisting of a plurality of separated and superimposed diffusing elements provided with coacting deflecting surfaces constructed and arranged on their sides facing the opening and adapted to be impinged upon by the liquid passing through said opening so that the liquid passing through the opening is divided into a plurality of separate and independent streams of liquid diverging towards and impinging against each other to form a zone of impact of said streams of liquid removed and in proximity to said spreading member and an area of sprayed or diffused liquid beyond said zone of impact.

In testimony whereof I hereunto affix my signature.

BERNARD STANLEY NELSON.
